UNITED STATES PATENT OFFICE.

PETER BALLAŽ, OF WEST NEW YORK, NEW JERSEY.

ORNAMENTAL COMBINATION WOOD, COAL, OIL, AND KEROSENE STOVE.

1,411,251.

Specification of Letters Patent. Patented Apr. 4, 1922.

Application filed November 1, 1921. Serial No. 512,083.

To all whom it may concern:

Be it known that I, PETER BALLAŽ, citizen of Czechoslovakia, residing at West New York, in the county of Hudson and State of New Jersey, have invented certain new and useful Improvements in Ornamental Combination Wood, Coal, Oil, and Kerosene Stoves, of which the following is a specification.

10 This invention relates to stoves, having more particular reference to a stove arranged either to burn coal, or to have an oil burner disposed in its firepot.

The invention has for a general object 15 to provide an improved stove of the kind set forth above, and further to provide a simple means for the simultaneous control of a multiplicity of burner wicks.

For further comprehension of the invention, and of the objects and advantages thereof, reference will be had to the following description and accompanying drawings and to the appended claims in which the various novel features of the invention 25 are more particularly set forth.

Fig. 1 of the drawings is a plan view of a stove constructed according to the invention.

Fig. 2 is a fragmentary horizontal section 30 illustrating particularly the ash sifting means, this view being taken on the line 2—2 of Fig. 4.

Fig. 3 is a front view.

Fig. 4 is a vertical sectional view at right 35 angles to Fig. 3, this view being taken on the line 4—4 shown in Figs. 2 and 3.

Fig. 5 is a detail plan view of the oil burner.

Fig. 6 is a vertical sectional view on the 40 line 6—6 of Fig. 5.

Fig. 7 is a detail elevation of the wick regulating means.

Fig. 8 is an enlarged fragmentary horizontal section on the line 8—8 of Fig. 6.

45 As here embodied my improved stove comprises a base 10 above which is an ash-pit 11 separated by a grate 12 from a fire-pot 13 of approximately globular shape. Above the fire-pot 13 is a vertically disposed cylindrical member 14 hinged at one side to the fire-pot as at 15. The sides of the fire-pot 13 and cylinder 14 are shown as provided with ornamental scroll-straps 16 and 17 one of the latter supporting the cylinder 14 in 50 a horizontal position when swung open. The

cylinder 14 is closed at its upper end by a top 18 in which is a removable lid 19. The vertical wall of cylinder 14 extends above the top 18 in the form of an annular flange upon which is seated an ornamental basin 60 20 provided with a series of vase-like elements 21 in which flowers may be kept, as indicated in Fig. 3. Just below the top 18 a flue opening 22 for the escape of the gases is provided, this opening being adapted to 65 be connected by suitable piping, a portion of which is indicated at 23, to the chimney.

The cylinder 14 has provided therein below the opening 22, an oven 25 closed by a door 26, draft spaces being left between 70 the sides of this oven and the walls of the cylinder.

The grate 12 is preferably of the lifting type, having trunnion elements 28 suitably supported in the stove walls, one of these 75 trunnion elements being formed with a squared end adapted to receive a suitable handle. A grate 12 rests at opposite sides on a fixed stop 29 and a movable stop 30, the latter being in the form of a short 80 arm pivoted as at 31 and provided with an operating handle 32.

The top of the base 10 forms the bottom of the ash-pit 11 and is formed with a circular depression 34 throughout which a 85 number of openings 35 are spaced. A sifter disk 36 rests in this depression being pivoted for rotation therein as at 37 and is provided with a number of openings 38. Fixed to the disk 36 is a handle 39 which extends outward through a suitable arcuate slot in the annular wall of the depression 34. An ash-pan 40 may be supported below the depression 34 to receive the ashes. The ash-pit 11 and fire-pot 13 are provided with suitable hinged doors 42 and 43.

In the use of the stove coal or like solid fuel is preferably burned during the winter, an oil burner being inserted in the fire-pot 13 for use in the summer months.

When oil is to be utilized as the fuel for the stove the oil burner shown in Figs. 5 and 6 is placed in the fire-pot 13, resting upon the grate 12. This burner comprises a circular receptacle or bowl 45 having a flat 100 top 46 in which a number of parallel rows of short vertical tubes 47 are fixed, the tubes 47 extending downward for a distance into the bowl and having flared upper ends located just above the bowl top 46. Round wicks 48 105 110

are inserted in these tubes 47 depending below the latter into the oil in the bowl.

These wicks 48 are all arranged for adjustment in unison and to this end a shaft 50 extends through the bowls 45 and has fixed thereon a series of worm pinions 51 which mesh with worm gears 52 on a series of shafts 53 which extend transversely to the shaft. These shafts 53 extend along beside the rows of tubes 47 and are provided with starwheels 54 which engage and move the wicks 48, the tube 47 being each cut out on one side as at 55 to accommodate the starwheels 54. The shaft 50 has a knurled head 56 on one end for purposes of rotation.

The bowl 45 has hinged to one side thereof as at 60 a flat disk cover 61 which is utilized to extinguish the flames of the wicks as follows:

20 The bowl 45 is of less size than the fire-pot 13, being insertible in the fire-pot through the top of the latter when the cylinder 14 is thrown back. Fixed to the cover 61, a short distance from its hinge point 60, is an ear 65 which is connected by a link 66 with a lug 67 on the fire-pot wall. By moving the bowl 45 backward or forward in the fire-pot the cover 61 is caused to close or open by the action of link 66 thereon. To move the bowl 45 back and forward a rod 68 is fixed thereto and passes outwardly through a suitable opening in the fire-box. In case it is not desired to use the cover opening and closing means just described a 35 finger 70 is pivoted in the cylinder 14 and has a handle 71 connected to it whereby it may be turned to engage with, or disengage from, the cover 61 to hold the latter raised.

If it is desired to use the oil burner above 40 the bowl 45 may be supported on a stand 75 while a suitable grill 76 may be supported above the bowl to receive the cooking utensils.

Having thus described my invention what 45 I claim as new and desire to protect by Letters Patent of the United States is as follows:

1. In a stove, a fire-pot, an oil burner rest-

ing freely in said fire-pot and movable bodily therein, and a cover for said oil burner 50 adapted to be automatically opened and closed upon movement of said burner in opposite directions in said fire-pot.

2. An oil burner comprising a bowl, a series of rows of vertical tubes extending into 55 said bowl from the top thereof, wicks in said tubes, a series of shafts extending along adjacent said rows of tubes, toothed wheels on said shafts adapted to engage said wicks, a shaft extending transversely to the said series of shafts, a plurality of worm pinions on said last shaft, and worm gears on the said series of shafts engaged by the said worm pinions.

3. An oil burner comprising a bowl, a series of rows of vertical tubes extending into said bowl from the top thereof, wicks in said tubes, a series of shafts extending along adjacent said rows of tubes, toothed wheels on said shafts adapted to engage said wicks, 70 a shaft extending transversely to the said series of shafts, a plurality of worm pinions on said last shaft, and worm gears on the said series of shafts engaged by the said worm pinions, the said tubes being cut out at 75 one side for access of the said toothed wheels to the said wicks.

4. In a stove, a fire-pot, an oil burner resting freely in said fire-pot and movable bodily therein, a cover hinged to said oil burner, and means for closing or opening said cover upon movement of said oil burner in opposite directions in said fire-pot.

5. In a stove, a fire-pot, an oil burner resting freely in said fire-pot and movable bodily therein, a cover hinged to said oil burner, and means for closing or opening said cover upon movement of said oil burner in opposite directions in said fire-pot, said means comprising a lug fixed to the fire-pot, an 90 ear fixed to the cover, and a link connecting said lug and ear.

In testimony whereof I have affixed my signature.

PETER BALLAŽ.
